UNITED STATES PATENT OFFICE.

DIAMOND ZAHARIS, OF SUSQUEHANNA, PENNSYLVANIA.

DISPLAY-STAND.

1,012,959.

Specification of Letters Patent. Patented Dec. 26, 1911.

Application filed September 3, 1911. Serial No. 848,440.

To all whom it may concern:

Be it known that I, DIAMOND ZAHARIS, a subject of the King of Greece, residing at Susquehanna, in the county of Susquehanna and State of Pennsylvania, have invented 5 new and useful Improvements in Display-Stands, of which the following is a specification.

This invention relates to display stands 10 and more especially to stands for the display of small articles such as candy, etc., and which is adapted to occupy a small amount of space and at the same time display a great variety of the articles to be exhibited, as will be more fully described in 15 the following specification, set forth in the claims and illustrated in the drawings, wherein,

Figure 1 is a perspective view of the 20 stand. Fig. 2 is a cross sectional view through same. Fig. 3 is a view of the end section of the stand.

The device is adapted to be made of sheet 25 metal or card board and is formed of four sides, 5, 6, 7 and 8, but it is obvious that the stand may be formed in a square or any other shape that may be desired. Each side consists of a series of steps having flat surfaces 30 9, upon which the goods are displayed, while substantially incline members 10 connect the flat surfaces and form a continuation of the sheet metal or card board. The upper end of each section consists of a vertical member 11, while the lower end terminates 35 in the horizontal strip 12 and on the inner side of each section is a wall 13 to which the section is secured by which it is braced and strengthened and is either pasted or soldered to same as may be found necessary. The upper end of the wall 13 is formed 40 with a vertical portion 14, while the lower end is provided with the horizontal portion 15 and the end of each section is beveled so that they may be assembled as shown in 45 Fig. 1.

After the sections are assembled, a top piece or cap 16 is placed thereon and its sides 17 hold the upper ends of the section together, and while the ends of the cap are 50 shown as being open, it is obvious that they

may be closed in order to prevent the dislocation of the end sections 6 and 8.

The lower part of the stand is held together by means of a tray 18, having the side flanges 19 into which the sections fit 55 and are substantially held together. Running through the side sections 5 and 7 are pegs 20, which support a tray 21 on the inside of the stand and serve to strengthen and brace same, while it may be at the same 60 time used as a means for holding an extra supply of the articles to be exhibited, and by simply removing one of the end sections, access may be given to this tray which may be drawn out and relieved of its supply to 65 replace articles removed from the outside of the stand.

This stand may be readily taken down for shipment and may be easily set up for use.

It is obvious that it may be modified and 70 its parts otherwise constructed or arranged without departing from the essential features above described.

What I claim as new and desire to secure by Letters Patent is,—

1. In a display stand, side and end sections, each of said sections comprising an inner wall, steps supported by and secured to each of said walls, a cap adapted to fit over the upper portion of said steps, a tray 80 adapted to receive the bottom portion of said sections, and a tray mounted between the sections for bracing the same.

2. In a display stand, side and end sections, each of said sections comprising an 85 inner wall having a vertical upper end and a horizontal lower end, steps supported by and secured to each of said walls, said steps having their upper and lower ends bent to correspond to the ends of the walls, a cap 90 having depending flanges adapted to fit over the vertical upper ends of the walls and steps, and a tray having upturned portions adapted to engage the horizontal lower ends of the walls and steps.

3. In a display stand, side and end sections, each of said sections comprising an inner wall having a vertical upper end and a horizontal lower end, steps having flat surfaces and inclined members engaging the 100

same, said steps supported by and secured to each of said walls, the steps having their upper and lower ends bent to correspond to the ends of the walls, a cap having a depending flange adapted to fit over the vertical upper end of the walls and steps, a tray having upturned portions adapted to engage the horizontal lower ends of the walls and steps, a tray having inclined flanges

mounted between the sections serving as a brace, and pins projecting laterally through the said sections to support the tray.

In testimony whereof I affix my signature in presence of two witnesses.

DIAMOND ZAHARIS.
